UNITED STATES PATENT OFFICE.

WILLIAM MARCROFT, OF CRANSTON, RHODE ISLAND, ASSIGNOR TO UNIVERSAL
WINDING COMPANY, A CORPORATION OF MAINE.

WINDING-MACHINE.

1,184,193.

Specification of Letters Patent.

Patented May 23, 1916.

Application filed July 21, 1913. Serial No. 780,275.

To all whom it may concern:

Be it known that I, WILLIAM MARCROFT, a citizen of the United States, residing at Cranston, in the county of Providence and 5 State of Rhode Island, have invented certain new and useful Improvements in Winding-Machines, of which the following is a specification.

My invention relates to winding machines 10 and consists particularly of improvements in the traverse-mechanism therefor.

The object of my improvement is to provide means for gradually shortening the traverse of the thread-guide from start to 15 finish of the winding to cause the cop or quill to be wound with tapered or conical ends.

A further object of my invention is to provide a traverse-shortening device which can 20 be applied to standard types of machines now generally known and used, without requiring any material change in the main parts of the mechanism thereof.

The invention is fully described in the 25 following specification, illustrated by the accompanying drawings, in which like letters of reference designate like parts.

In the drawings:—Figure 1 is a front elevation of a usual type of winding machine 30 showing my new traverse-controlling mechanism applied thereto; Fig. 2 is an enlarged view of the essential parts of the new device; Fig. 3 is an end elevation of the same; Fig. 4 is a part sectional view, taken on the 35 line X—X of Fig. 1, looking in the direction indicated by the arrow α ; Fig. 5 illustrates the style of cop or quill wound on machines fitted with my improved device.

Referring to Fig. 1, the machine in general 40 as here shown, is of a well known type substantially like that described and illustrated in United States Patent No. 589,587 granted to S. W. Wardwell Sept. 7, 1897 and widely used for winding shuttle cops or quills by 45 the Universal or V-wind system. It consists essentially of a rectangular frame A having parallel uprights a , a formed with bearings for the horizontal winding-spindle B and cam-shaft C. The spindle B is driven 50 through the medium of a driving-pulley b adapted to be rotated by a suitable belt, not here shown, which is shifted onto the loose pulley b' when it is desired to stop the machine. The spindle B also carries a pulley

b^2 which is connected by a belt b^3 to a pulley 55 b^4 on a shaft D. The shaft D is mounted to rotate in bearings on a frame d which is pivoted at d' , d' on the cam-shaft C. At one end the shaft D carries a pinion d^2 which meshes with a gear c on the cam-shaft C. 60 The pulley b^4 is preferably of the expansible type commonly used on winding machines of this style and can be adjusted to vary the diameter of its rim by simply turning the hand-nut b^5 . Through this adjustment the 65 ratio between the speed of the spindle B and that of the cam-shaft C can be varied to regulate the laying of the yarn or thread by the reciprocating thread-guide in a manner well known to those versed in the art. 70

The cam C' is mounted fast on the shaft C and is driven thereby, through the connections above described, to impart reciprocation to a horizontal traverse-bar E. The bar E is arranged parallel with the winding-spindle B and is mounted to slide longitudinally in the bearings a' , a' of the frame A. The bar E is preferably arranged to project from both sides of the frame A to adapt it to carry two thread-guides G so that the 80 machine can be arranged to wind two quills at a time, one being supported at each end of the winding-spindle B. As both ends of the machine are similar, however, I have preferred to here illustrate the traverse- 85 mechanism for one quill only, it being understood that this mechanism is duplicated on the opposite side of the frame A.

Arranged in the rear of the traverse-bar E and supported fixedly in bearings a^2 of 90 the frame A, see Fig. 3, is a horizontal rod F extending parallel with the rod E. On the outer end of the rod F is supported a bracket H which carries an end-bearing h for the cop-tube z , see Fig. 2. The end-bearing h preferably takes the form of a live spindle rotatable in a bushing h' and projecting therefrom to enter the bore of the tube z . The opposite end of the tube z is supported on the reduced end b^6 of the winding-spindle B and is preferably formed with a slot z' which is engaged by a key or spline b^7 on the spindle to rotate the tube. The bushing h' is retractable in the bracket H to allow the insertion and removal of the tube 105 z as usually provided for in machines of this class.

The thread-guide G is mounted on the

traverse-bar E through the means of an arm or holder G' arranged to oscillate about the axis of the bar to allow the guide to move outward away from the surface of the cop-tube as the yarn is built thereon. Referring to Figs. 1 and 4, the traverse-bar E is reciprocated from the cam C' through the engagement of the groove c' in the latter with a roll j carried by a cross-head J attached to the bar. One end of the cross-head J surrounds the bar E and is clamped thereon by means of the binder-screw j'. At its opposite end the cross-head J is fitted to the under side of the rod F and a spring-plate j'', secured in position by the screw j', reaches over to engage the top of the rod F to hold the cross-head in proper relation to the cam C'. A stud j''' is riveted in a hub j'' at the center of the cross-head J and serves as a bearing for the roll j which engages with the cam-groove c'.

The above described parts are substantially the same in structure and arrangement as those employed generally in machines of this type and my new devices are applied thereto in the manner and for the purpose as now described.

Heretofore it has been the common practice to reciprocate the thread-guide with a constant traverse throughout the winding of the cop or quill. This naturally results in building up the ends of the quill with a flat formation; that is to say, the ends will be square with the axis of the quill. In winding some varieties of thread, such as hard, glossy silk and other like materials, it has been found very difficult to build the quills with perfect ends while employing this style of winding. Owing to the slippery quality of the thread the coils of winding are liable to slide off the ends of the quill and fall down on to the tube, thereby causing a malformed package from which the yarn cannot be unwound without snarling and breaking. To obviate this defect in the quills it has before been proposed to wind them with tapered or conical ends as illustrated particularly in Fig. 5. Previous to my present invention, however, it has required special machines, built particularly for winding in the manner described, to produce taper-ended quills of this form. My new improvement makes it possible to adapt a usual style of quill-winder for this style of winding and the manner of carrying out the improvement will be next described.

It will be observed from the foregoing explanation that the traverse-bar E is given a uniform reciprocation from the cam C' throughout the operation of the machine. As usually provided in machines of this type the thread-guide is fixedly attached to the traverse-bar so that the guide also has a constant extent of traverse in relation to the cop-tube on which the quill is wound.

In my present improvement I maintain the reciprocation of the traverse-bar uniform, but provide for shifting the thread-guide longitudinally of the bar during the movement of the latter so as to effect the gradual shortening of the traverse of the guide from start to finish of the winding. To adapt the guide G for this shifting movement in relation to the bar E it is mounted on a sleeve g which slides on the bar. The guide-holder G' is formed as a bifurcated arm having two legs g', g' surrounding the sleeve g to adapt it to pivot thereon. Between the legs g', g' is a collar g'' secured in position by the binder-screw g''' and formed with two cam-shaped prongs g'''' and g'''''', see Fig. 3. The prong g''''' is adapted to contact with the rear face of the guide-holder G' to limit the movement of the guide G toward the axis of the quill; while the other prong g''''' is engaged by a flat spring g'''' secured to the guide-holder G' at its upper end by the screw g'''. The end of the spring g'''' rides on the cam-face g'''' of the prong g''''' and tends to force the guide G toward the axis of the cop-tube, and as the yarn is built up thereon the movement of the guide away from the quill is resisted by the action of the spring, so as to maintain the guide always bearing firmly against the surface of the winding. Attached to the upper end of the guide-holder G' is a guiding-eye g'' through which the yarn or thread y leads from above, and thence it passes through a notch g'''' in the guide G, see also Fig. 2, and onto the cop-tube z. The sleeve g on which the guide-holder G' is mounted is formed with a head g'''' at one end, to which is attached the end of a connecting-rod or link K. Preferably the link K is provided with a series of holes k, k, etc., through any one of which is passed a screw g'''''' screwed into the head g'''' of the sleeve g. Through this means the initial position of the guide G on the traverse-bar E may be adjusted in accordance with the length of throw of the cam C', it being understood that the cam can be changed for different lengths of traverse as usually provided. The automatic shifting of the guide on the traverse-bar is controlled through the link K by the means next described.

Referring to Figs. 1, 3 and 4, a bracket L is attached to the top of the frame A by means of the screws l, l. Mounted to turn in bearing-lugs l', l' on said bracket is a rock-shaft M having its outer end bent at right-angles to form the crank-arm m. Secured to the end of the crank-arm m by a screw m' is a link m'' formed with its lower end curved inwardly, below the winding-spindle B, to adapt it to be secured to a swinging frame N. Referring particularly to Figs. 2 and 3, the frame N is of fork-like construction having a hub n pivoted on the

rod F and two upwardly curved arms n' , n' . The upper ends of the arms n' , n' are provided with slots n^2 , n^2 adapted to receive the ends of a rod or pin o which serves as an axial bearing for a pressure-roll O. The roll O is preferably constructed of wood or other similar material and has a smooth, peripheral surface adapted to contact with the yarn or thread as the latter is wound on the tube z. The roll O is maintained in contact with the surface of the winding by means of weights p suspended at the end of a rod P which extends rearwardly from the frame N. Preferably the rod P is driven into an arm n^3 projecting from the hub n of the frame N and the weights p are hung on a rod p' suspended from a spring p^2 hooked into a hole p^3 in the rod P. The spring p^2 serves to take the shock of any sudden movement of the frame N and prevents the weights p from jumping up and down on the rod p' . In this way the effects of momentum and inertia on the roll O are partially compensated for. The link m^2 is secured to the inner arm n' of the frame N by any suitable means, such as the screw m^3 , and as the roll O is forced downward by the increase in diameter or growth of the quill the crank-arm m and rock-shaft M are turned in the direction indicated by the arrow 2, Fig. 3. Secured to the rock-shaft M between the bearing-lugs l' , l' is an arm R having its hub r clamped to the shaft by the binder-screw r' . The arm R extends laterally from the shaft M in the opposite direction from that of the crank-arm m and its outer end is reduced at r^2 to adapt it to engage a hole s in a vertical slide S. As shown in Figs. 2 and 3, the slide S is preferably formed of sheet-metal with a relatively narrow portion s' fitted to slide in a slot or guideway l^2 formed in the downwardly-extending member l^3 of the bracket L. The guideway l^2 might be constructed with dovetail edges fitted to the slide S to retain the latter in place, but as here shown I prefer to employ a cover or plate l^4 fastened to the bracket L by the screws l^5 , l^5 to hold the slide in the guideway. At its upper end the slide S is bent forward in the right-angled arm s^2 which is then bent downwardly again at s^3 and terminates in the relatively-long, guiding-member or track s^4 formed with the horizontal slot s^5 . It will be observed that the rocking of the shaft M from the turning of the crank-arm m will cause the slide S to move up and down in its guideway l^2 . Secured to the inner end of the link K by the screws t, t is a V-shaped, elbow-member T having one arm t' reaching upwardly adjacent the track s^4 . A stud t^2 reaches through the slot s^5 in the track s^4 and is screwed into the end of the arm t' of the member T. The stud t^2 is adapted to slide

in the slot s^5 as the thread-guide G and its connecting rod or link K reciprocate with the traverse-bar E.

Referring to Figs. 2 and 4, U designates a rockable arm or lever formed at its upper end with a longitudinal slot u.

Fastened to the front of the bracket L is a vertically-adjustable plate L' which is held in position by the screws l^6 , l^6 extending through the slots l^7 , l^7 . The plate L' bears against two raised ledges or end abutments l^8 , l^8 on the front of the bracket L so that an open space is left between the rear face of the plate and the front face of the bracket throughout the greater portion of the length of the plate. In this way the lever U is adapted to be held in place against the front face of the bracket L and is arranged to pivot on a stud or pin l^9 projecting rearwardly from the plate L'. The stud l^9 engages the slot u in the lever U to allow the latter to slide up and down during its swinging motion as it oscillates about the axis of the stud. By loosening the screws l^6 , l^6 the plate L' can be adjusted up and down on the bracket L to vary the position of its pivot stud l^9 and in this way the range of movement of the lever U can be altered as more particularly described hereinafter. The lever U is given a reciprocatory-rocking movement, somewhat like the link-motion of a steam-engine, through its connection with the reciprocating cross-head J.

Referring particularly to Fig. 4, which shows the slide S removed from in front of the lever U, a stud or pin u' is riveted through the lever U near its lower end and projects rearwardly therefrom to adapt it to engage a hole j^5 in a lug j^6 on the cross-head J. Secured against the front face of the lever U is a bridge-member U' formed with the major portion of its length offset from the lever, so as to leave a space between the two. The bridge-member U' is fastened to the lever U by means of a screw u^2 and stud u^3 and is formed with a longitudinal slot u^4 extending throughout a part of the length of its offset portion.

Referring to Figs. 2, 3 and 4, the end of the link K opposite to that connected with the thread-guide G projects between the outer face of the lever U and the inner face of the bridge-member U' and carries a stud u^5 engaging the slot u^4 in the latter. The stud u^5 also projects through a hole in the apex extremity of the elbow-member T which overlies the front face of the bridge-member U'. In other words, the end of the link K and its overlapping extension or elbow-member T straddle the bridge-member U' and are linked thereto and to the lever U by means of the stud u^5 which is adapted to slide in the slot u^4 . The outer ends of the studs u^5 and u^3 are scored with pe-

ripheral grooves u^6 and u^7 , respectively, and a coiled spring V is stretched between the studs with its ends hooked around said grooves. The tendency of the spring V is 5 to draw the stud downwardly in the slot u^4 .

The method of operation of my complete device is as follows: The cop-tube z is placed in position by seating one of its ends on the end of the winding-spindle B and the other on the spindle-bearing h , and the yarn or thread y is led from its source of supply through the guiding-eye g^9 and notch g^{10} of the thread-guide G and then secured to the tube z . Through 15 the effect of the weights p on the frame P the pressure-roll O will be held against the surface of the tube z at the beginning of the winding, as illustrated in Figs. 1 and 3. When the machine is started by shifting 20 the driving-belt on to the pulley b the spindle B will rotate the tube z and, through its connections with the cam-shaft C will turn the cam C' to reciprocate the traverse-bar E. As the yarn builds up on the tube z 25 the pressure-roll O will be forced downwardly, thereby swinging the frame N on the rod F and causing the link m^2 to turn the crank-arm m in the direction indicated by the arrow 2, Fig. 3. The movement of 30 the crank-arm m turns the rock-shaft M to raise the arm R and slide S is thus gradually moved upwardly in its guideway t^2 on the bracket L.

During the reciprocation of the cross-head J and traverse-bar E, the lever U, which is connected with the former by the pin u' , is caused to oscillate back and forth between the positions shown by full lines and dot-and-dash lines in Fig. 2, its upper 35 end sliding on the pivot-stud l^9 . At the beginning of the winding the link K is held in the position illustrated in Fig. 1 with the stud u^5 in the same horizontal plane with the screw g^{12} at its opposite end. With 40 the parts in this position the link K will have a right-line movement with respect to the cam C' exactly equal to the reciprocatory movement of the traverse-bar E, and therefore the thread-guide G will be traversed with the full extent of throw of the 45 bar.

As the lever U oscillates in the manner above described the elbow-member T and link K, which are connected thereto, move 50 in synchrony therewith and the stud t^2 on the arm t slides in the slot s^5 of the guiding-track s^4 . Now, as the slide S and its track s^4 are raised through the movement 55 of the roll O, under the influence of the growth in diameter of the winding, the stud u^5 at the end of the link K will be moved gradually upward in the slot u^4 of the bridge-member U'. Since the bridge-member U' forms a part of the lever U the 60 end of the link K is therefore caused to 65

gradually approach the axis of oscillation of said lever U. By referring to Fig. 2 it will be seen that as the link K is moved upwardly on the lever U the oscillating movement of the latter will cause the link to 70 shift the position of the sleeve g on the traverse-bar E at each extreme of throw or traverse of the bar. In other words, when the traverse-bar E is carried to the outer end of its throw, as illustrated by full lines in Fig. 2, the lever U will act to draw the link K inwardly so that the sleeve g is shifted on the traverse-bar to hold the thread-guide from traversing through the full extent of throw of the bar. In the same 80 way, when the traverse-bar E is carried to the opposite extreme of its throw the lever U will have been rocked to the position shown by dot-and-dash lines in Fig. 2, and the link will be moved in the other direction, or outwardly with respect to the traverse-bar, so that the thread-guide will be prevented from continuing the full extent of traverse inwardly with the bar. In this 85 way the movement of the thread-guide G is restricted or retarded at the end of each stroke of the traverse-bar and thereby the extent of traverse of the guide is gradually shortened as the cop increases in diameter. The result of this restriction or shortening 90 of the traverse of the guide is to build the quill with the layers of winding of gradually diminishing lengths so that the ends of the quill take on a tapered or conical formation as illustrated by the outline Y in Fig. 95 2, and by the more complete representation in Fig. 5.

By adjusting the plate L' up and down on the bracket L the pivot l^9 for the lever U can be raised or lowered to alter the range 100 of action of the lever U. Through this means the angularity of the lever U with respect to the traverse-bar E at the extremes of its oscillation can be increased or diminished as required to effect a greater or less 105 limitation or shortening of the traverse of the thread-guide. In this way the degree of taper at the ends of the quill can be varied as desired or in accordance with different conditions in the winding or of the 110 materials being wound. When it is required to wind quills of different length a cam of different throw is substituted for the cam C' and the connection of the link K to the guide G is adjusted through the 115 means of the holes k as previously described.

I am aware that it is not new in the art to wind cops or quills with conical ends and I am familiar with several and various devices for accomplishing this purpose. 120 Heretofore, however, so far as I am aware no mechanism for this purpose has been devised which is capable of being attached to standard types of winding-machines, 125 already in use, without affecting the general 130

arrangement and construction of the operating parts thereof. Furthermore, it is my belief that the present invention is the first wherein the traverse-bar on which the 5 thread-guide is mounted is given a constant extent of reciprocation while the guide itself is shifted thereon through automatically-operated means to cause a shortening of its traverse as the cop increases in diameter.

10 Various modifications might be made in the form and structure of the parts of my device without departing from the spirit or scope of the invention; therefore,

15 Without limiting myself to the exact arrangement shown and described, what I claim is:—

20 1. In a winding machine, the combination with a rotating winding-spindle and a reciprocating traverse-bar, of a thread-guide mounted on said traverse-bar, and means to shift said guide bodily longitudinally of the bar at the extremes of traverse of the latter to shorten the layers of winding in the cop as the latter increases in diameter.

25 2. In a winding machine, the combination with a rotating winding-spindle and a reciprocating traverse-bar, of a thread-guide mounted on said traverse-bar, and means controlled by the growth of the winding to shift the guide bodily longitudinally of the bar during each reciprocation of the latter to gradually shorten the traverse of the yarn on the cop as the latter increases in diameter.

30 3. In a winding machine, the combination with a rotating winding-spindle, of a cam rotated therefrom, a traverse-bar reciprocated by said cam with a constant extent of throw, a thread-guide mounted on the traverse-bar to adapt it to recede from the winding-spindle as the cop increases in diameter, and means to shift the guide bodily longitudinally of the traverse-bar during each reciprocation of the latter to effect a gradual shortening of the layers of 35 winding as the cop increases in diameter.

40 4. In a winding machine, the combination with a rotating winding-spindle and a reciprocating traverse-bar, of a thread-guide mounted on the traverse-bar to adapt it to recede from the winding-spindle as the cop increases in diameter, and means to shift the guide bodily longitudinally of the traverse-bar during each reciprocation of the latter to effect a gradual shortening of the layers of 45 winding as the cop increases in diameter.

45 5. In a winding machine, the combination with a rotating winding-spindle and a reciprocating traverse-bar, of a thread-guide mounted on the bar to adapt it to recede from the winding-spindle as the cop increases in diameter, a link connected with 50 said guide, and means to move said link

to shift the guide bodily longitudinally of the bar at the extremes of traverse of the latter to gradually shorten the layers of winding as the cop increases in diameter.

55 6. In a winding machine, the combination with a rotating winding-spindle and a reciprocating traverse-bar, of a thread-guide mounted on the bar to adapt it to recede from the winding-spindle as the cop increases in diameter, and means to shift 70 said guide bodily inwardly from the ends of traverse of the bar at each reciprocation of the latter to gradually shorten the layers of winding as the cop increases in diameter.

75 7. In a winding machine, the combination with a rotating winding-spindle and a reciprocating traverse-bar, of a sleeve 80 slidable on said bar, a thread-guide pivoted on the sleeve to adapt it to move outwardly from the winding-spindle, and means to shift the sleeve longitudinally of the bar during each reciprocation of the latter to progressively shorten the traverse of the guide from start to finish of the winding.

80 8. In a winding machine, the combination with a rotating winding-spindle and a reciprocating traverse-bar, of a thread-guide mounted on the bar to adapt it to recede from the winding-spindle as the cop increases in diameter, means to shift the 90 guide bodily longitudinally of the bar during each reciprocation of the latter, and means adapted to bear on the winding to control the shifting means to cause the guide to lay the yarn with a gradually decreasing 95 extent of traverse as the cop increases in diameter.

90 9. In a winding machine, the combination with a rotating winding-spindle and a reciprocating traverse-bar, of a thread-guide mounted on said bar to adapt it to recede from the winding-spindle as the cop increases in diameter, and means actuated from the reciprocation of the traverse-bar 100 to alter the position of the guide longitudinally of the bar at the extremes of throw of the latter to cause the guide to wind the yarn with a gradually decreasing extent of traverse throughout the building of the cop.

100 10. In a winding machine, the combination with a rotating winding-spindle and a reciprocating traverse-bar, of a thread-guide mounted on said bar to be reciprocated therewith, a lever oscillated from the movement of said bar, means connecting said 110 lever with the guide to shift the guide bodily longitudinally of the bar during its reciprocation therewith, and means controlled by the growth in the winding to actuate the shifting-means to progressively shorten the 115 traverse of the layers of the yarn as the cop increases in diameter.

11. In a winding machine, the combination with a rotating winding-spindle and a reciprocating traverse-bar, of a thread-guide 120

125

mounted on said bar to be reciprocated therewith, a lever oscillated from the movement of said bar, means connecting said lever with the thread-guide, and automatically-operated means to shift the connecting-means on the lever to alter the position of the guide longitudinally of the bar at the extremes of traverse of the latter to progressively shorten the layers of winding as the cop increases in diameter.

12. In a winding machine, the combination with a rotating winding-spindle and a reciprocating traverse-bar, of a thread-guide mounted on said bar to be reciprocated therewith, a pivoted lever oscillated from the movement of said bar, means connecting said lever with the guide to shift the latter longitudinally of the bar during its reciprocation therewith to progressively shorten the traverse of the guide, and means to regulate the movement of the lever to vary the extent of shifting of the guide to control the degree of taper at the ends of the cop.

13. In a winding machine, the combination with a rotating winding-spindle and a reciprocating traverse-bar, of a thread-guide mounted on the bar, a pivoted lever oscillated from the movement of the bar, means connecting said lever with the thread-guide to shift the latter longitudinally of the bar during its reciprocation therewith, and means to adjust the pivot of the lever to regulate the angular movement of the latter to control the extent of shifting movement of the guide with respect to the bar.

14. In a winding machine, the combination with the rotating winding-spindle and reciprocating traverse-bar, of a thread-guide mounted on the bar, a lever oscillated from the movement of the bar, means connecting said lever with the thread-guide, and means operated from the growth in diameter of the winding to shift the point of connection of said means on the lever to progressively shorten the traverse of the guide as the cop increases in diameter.

15. In a winding machine, the combination with the rotating winding-spindle and reciprocating traverse-bar, of a thread-guide mounted on the bar, a lever oscillated from the movement of the bar, means connecting said lever with the thread-guide, a pressure-roll adapted to contact with the surface of the cop, and means operated by said roll during the increase in diameter of the winding to shift the connecting-means on the lever to progressively shorten the traverse of the guide from start to finish of the cop.

16. In a winding machine, the combination with the rotating winding-spindle and reciprocating traverse-bar, of a thread-guide mounted on the bar, a lever oscillated from the movement of the bar, a link connected to the guide with its opposite end slideable on the lever, means to slide said link toward

the axis of the lever, and means adapted to bear on the surface of the winding to operate said sliding-means to effect a progressive shortening of the traverse of the guide throughout the building of the cop.

17. In a winding machine, the combination with the rotating winding-spindle and reciprocating traverse-bar, of a thread-guide mounted on the bar, a lever oscillated from the movement of the bar, a link connected to the guide with its opposite end adapted to slide on the lever, a track for guiding the movement of the link with respect to the axis of the lever, and means controlled by the growth in diameter of the winding to move the track and shift the point of connection of the link on the lever to progressively shorten the traverse of the guide.

18. In a winding machine, the combination with the rotating winding-spindle, of a reciprocating thread-guide, means to reciprocate the guide, a lever oscillated from said means, a link pivoted at one end to said guide and pivotally connected at its opposite end to the lever to adapt it to slide thereon, a track for determining the path of travel of the connecting point of the link with respect to the axis of the lever, and means controlled by the growth in diameter of the winding to move the track and shift the link on the lever to progressively shorten the traverse of the guide.

19. In a winding machine, the combination with a rotating winding-spindle, of a cam rotated therefrom, a cross-head reciprocated from said cam, a pivoted lever connected to the cross-head to be oscillated thereby, a thread-guide, a link connected to said guide with its opposite end slideable on the lever, a track for guiding the movement of the link with respect to the axis of the lever, and means controlled by the growth in diameter of the winding to move the track and shift the point of connection of the link on the lever to progressively shorten the traverse of the guide.

20. In a winding machine, the combination with the rotating winding-spindle, of a reciprocating thread-guide, means to reciprocate said guide, a lever oscillated from said means, a link connected to the guide at one end with its opposite end adapted to slide on the lever, a track, means on the link adapted to slide on the track during the reciprocation of the guide, and means controlled by the growth of the winding to move the track to shift the point of connection of the link on the lever to progressively shorten the traverse of the guide throughout the building of the cop.

21. In a winding machine, the combination with the rotating winding-spindle, of a reciprocating thread-guide, means to reciprocate said guide, a slotted lever arranged to oscillate and reciprocate on a pivot ex-

- tending through its slot, means to actuate said lever from the guide-reciprocating means, a link connected to the guide at one end with its opposite end adapted to slide 5 on the lever, and means controlled by the growth of the winding to shift the point of connection of said link on the lever to progressively shorten the traverse of the guide throughout the building of the cop.
- 10 22. In a winding machine, the combination with the rotating winding-spindle, of a reciprocating thread-guide, means to reciprocate said guide, a lever oscillated from said means, a link connected to the guide at one end with its opposite end adapted to slide on the lever, a slide formed with a track, means on the link adapted to slide on the track during the reciprocation of the guide, and means adapted to bear on the 15 winding to be moved therefrom to move the slide and shift the point of connection of the link toward the axis of the lever as the cop increases in diameter.
- 20 23. In a winding machine, the combination with the main frame, of a winding-spindle rotatable in bearings on the frame, a cam connected to be rotated therefrom, a traverse-bar arranged to slide in bearings on the frame, a cross-head on the bar connecting the latter to be reciprocated from the cam, a thread-guide mounted on the traverse-bar to be reciprocated therewith, a bracket attached to the frame, a lever pivoted on the bracket with its opposite end 25 connected to the cross-head, a link connected with the guide at one end with its opposite end adapted to slide on the lever, a slide arranged to move in a bearing on the bracket,
- a guiding-track on said slide, means on the link adapted to slide on the track, and means 40 adapted to engage the winding to move the slide and shift the point of connection of the link on the lever.
24. In a winding machine, the combination with the rotating winding-spindle, of a reciprocating thread-guide, means to reciprocate said guide, a lever oscillated from said means, a link connected with the guide with its opposite end adapted to slide on the lever, a pressure-roll adapted to bear on the 45 winding, a rock-shaft connected with said roll to be rocked therefrom during the growth of the winding, and means operated by the movement of the rock-shaft to shift the point of connection of the link on the lever to progressively shorten the traverse of the guide throughout the building of the cop.
25. In a winding machine, the combination with a rotating winding-spindle, of a reciprocating traverse-bar, a thread-guide mounted on the bar to be reciprocated therewith, a link connected with the guide, a lever connected with the traverse-bar and adapted to be operated through the reciprocation of the bar, and means connecting the link with the lever and adapted to be actuated from the growth in diameter of the cop to vary the effect of the lever on the link to progressively shorten the traverse of the guide.

In testimony whereof I affix my signature in presence of two witnesses.

WILLIAM MARCROFT.
